UNITED STATES PATENT OFFICE

2,450,087

OPEN-FLAME HEATED CONTINUOUS
FURNACE

Fred N. Hays, Edgewood, Pa.

Application April 27, 1944, Serial No. 532,996

2 Claims. (Cl. 263—43)

1

This is a continuation-in-part of an application filed May 20, 1942, Serial No. 443,801, and relates to open-flame heated continuous furnaces and particularly to the type having flues arranged to provide sectionalized heating of the work traveling through the furnace, the object being to provide a furnace of this type which may be operated with the atmospheric pressure level inside the furnace in its high temperature zone adjusted about at the hearth or work top level and which does not require that the pressure at the hearth level in the high temperature zone be materially above atmospheric pressure to make the flue system work, the latter practice being objectionable since it blows the hotter flame stingers through the various furnace openings to an excessive degree.

Specific examples of furnaces constructed in accordance with the principles of this invention are illustrated by the accompanying drawings in which:

Figure 1 is a vertical section;

Figure 2 is a horizontal section; and

Figure 3 is a view similar to Figure 1 except for showing a modification of the invention.

More specifically, in the case of the first example the furnace is of the continuous type having a work entrance 1 for one end and a work exit 2 for its other end with a hearth 3 over which the work travels while going from the entrance to the exit. The furnace is heated by having at least one open-flame burner 4 near the exit 2 and provision is made for sectionalized heating of the work by the furnace having at least one flue 5 near the exit 2 and at least one other flue 6 near the entrance 1 in conjunction with having a roof providing a lower portion 7 near the entrance 1 and a higher portion 8 near the exit 2.

The work travels through the furnace on skids 9 and, preferably, the furnace is provided with at least one other burner 10 beneath the skids 9 that are under the lower roof portion 7. In a furnace of any material width there is a row of the burners 4 and a row of the burners 10 extending transversely of the furnace, and the flues 5 and 6 are usually each in the form of a multiplicity of flue passages extending in a row transversely of the furnace, all to the end of obtaining laterally uniform heating. The flue 5 is provided with a damper 11 and the flue 6 is provided with a damper 12, both flues connecting with a stack 13 by way of a stack connection flue 14 common to both the flues 5 and 6 but which functions to provide a longer stack connection for the flue 5 and a shorter stack connection for

the flue 6 as these connections compare to each other in length. This means there is more suction available in the flue 6 than in the flue 5.

In operation, the work is introduced to the skids 9 through the entrance 1 and is then moved over the skids through the furnace until it is at the exit 2 from which it is withdrawn. At least the burner 4 is operated and due to the height of the roof portion 8 there is created a high temperature zone beneath this roof portion, at least some of the products then exhausting through the flue 6 and forming a low temperature or pre-heating zone beneath the lower roof portion 7, the dampers 11 and 12 being operated as required to maintain the high temperature zone beneath the higher roof portion 8 at the temperatures demanded to bring the work to proper temperature. The burner 10 is operated as required to heat the bottom of the work to attain a relatively uniform preheating of the work prior to its reaching the high temperature zone.

The present invention is characterized by positioning the flue 5, which is the one near the exit 2, at least adjacent the level of the hearth 3 and not therebelow, although this flue may be slightly above the level of the hearth. Since it is preferable to maintain the atmospheric pressure level, in the high temperature zone, at about the hearth level, or very slightly thereabove so that it comes about at the level of the top of the work being heated, the flue 5 should not be placed so high, such as in the roof portion or above the burner 4, as to result in a construction preventing the maintenance of the atmospheric pressure level at or close to the level of the hearth. With this arrangement of the flue 5 it exhausts the furnace atmosphere at a point where this atmosphere has a pressure that about at least equals the atmospheric pressure, or which is slightly above atmospheric pressure, so the flue 5 can function properly in spite of its long stack connection, which reduces the suction available by reason of the stack effect, and without raising the pressure of the furnace atmosphere in the high temperature heating zone beneath the higher roof portion 8 to a degree resulting in the excessive blowing of hot flame stingers through the various furnace openings.

In the second example the flue near the exit 50 is in the form of a flue 15 in the furnace wall opposite the traveling direction of work over the hearth 3, while the latter terminates short of this wall, the exit being in the form of an exit 16 through this wall, having the flue 15, and at a position beneath the flue 15, that is near this exit

16, the furnace having means for carrying work from the hearth 3 down through this exit 16, which means is in the form of a skid decline 17. With this arrangement the atmospheric pressure level may also be maintained close to the hearth level 3, or at this level, in the high temperature zone and still have the flue 15 function properly, even though it is provided with the longer stack connection, the flue 15 again being adjacent the level of the hearth 3 but not therebelow. In this type of furnace it was formerly thought necessary to position the flue 15 beneath the decline 17 so as to prevent air sucked in through the exit 16 from going to the high temperature zone beneath the roof portion 8, but it is to be noted in the construction disclosed herein that air cannot go into this high temperature zone because the position of the flue 15 permits the positioning of the atmospheric pressure level existing in this zone about at the hearth level, the pressure above this level being above atmospheric pressure and therefore excluding the possibility of air being sucked into it. Furthermore, any air that might get sucked in merely short circuits from the exit to the flue 15 without cooling the high temperature zone. As explained in the case of the first example, the flue 15 is provided by a multiplicity of flues extending transversely of the furnace in the case of a furnace of any material width.

Both examples are intended to heat metal bars moved transversely through the furnace in contact with each other on the skids 9, the bars being introduced and removed longitudinally through the exits 1 and 2 in the case of the first example, while the second example is of the type having an entrance 18 through which the bars may be introduced laterally, the exit 16 likewise being wide enough so that the bars can discharge laterally, which means that the bars are not longitudinally introduced and removed in the case of this second example. Since the bars contact one another the atmospheric pressure level may be lifted by proper operation of the furnace to about at the level of the tops of the bars, their contact with one another and the fact that their bottoms are shielded by the hearth 3 reducing the hazard of oxidation. If the bars were separated, or were other objects which could not provide mutual protection by intercontact, it would be better practice to lower the atmospheric pressure level, again by proper operation of the furnace, to about the level of the hearth. In either

case the flues 5 and 15 function properly without greatly increasing the furnace pressure for the purpose of making the flues operate.

I claim:

- 5 1. In a continuous heating furnace having a horizontal hearth adapted to support work in its travel through the furnace, a roof and walls enclosing said hearth, a work entrance and a work exit in the walls adjacent opposite ends of said hearth, at least one open flame burner adjacent the work exit, at least one flue opening adjacent the work entrance, at least one flue opening adjacent the work exit, and stack connections for said flue openings, the improvement which comprises having the lower limiting position of said flue opening adjacent the work exit at the level of the horizontal hearth, which enables the furnace to be controlled with the atmospheric pressure level at hearth level.
- 10 2. In a continuous heating furnace having a horizontal hearth adapted to support work in its travel through the furnace, a roof and walls enclosing said hearth, a work entrance and a work exit in opposite end walls, at least one open flame burner adjacent the work exit, at least one flue opening adjacent the work entrance, at least one flue opening adjacent the work exit, and stack connections for said flue openings, the improvement which comprises locating said flue opening adjacent the work exit in the end wall above the level of the horizontal hearth to enable the furnace to be controlled with the atmospheric pressure level at hearth level.
- 15 30

FRED N. HAYS.
